US00D689867S

(12) **United States Design Patent**
Yamaguchi et al.

(10) **Patent No.:** US D689,867 S
(45) **Date of Patent:** ** Sep. 17, 2013

(54) **SCANNER**

(75) Inventors: **Masashi Yamaguchi**, Kawasaki (JP); **Yoshitomo Oota**, Tokyo (JP); **Hiroshi Ito**, Tokyo (JP); **Minoru Sashida**, Ageo (JP); **Kazuaki Sakuta**, Kawasaki (JP); **Yasushi Fujii**, Kawasaki (JP)

(73) Assignee: **Canon Densi Kabushiki Kaisha**, Saitama-ken (JP)

(**) Term: **14 Years**

(21) Appl. No.: **29/412,570**

(22) Filed: **Feb. 6, 2012**

(30) **Foreign Application Priority Data**

Aug. 9, 2011 (JP) 2011-018223

(51) **LOC (9) Cl.** **14-02**

(52) **U.S. Cl.**

USPC **D14/422**

(58) **Field of Classification Search**

USPC D14/420, 422, 425, 462-470, 424, D14/389, 125, 399; D18/54, 55, 50, 53, D18/36-39, 14, 18-21, 49, 46, 52, 56, 51, D18/54.4; D13/164, 168; 358/400, 401, 358/448, 474, 486-488, 496, 497, 494, 473, 358/302, 468, 498; 382/312, 317, 321, 315; 400/613, 613.1-613.4, 690.1-690.4, 691-694, 400/88, 175; 399/107, 379, 380, 211, 212; 235/462.11, 462.41, 472.01, 470, 462.43; 361/680, 681; 378/177, 187, 188; 101/93.4, 101/269; 355/78; D24/165, 169, 186; 600/502, 503, 499, 494, 490, 485, 500, 492, 600/480, 493, 495, 479; 128/900; 16/286; 347/104, 109, 5; 271/186, 225, 126, 121, 271/137, 138

See application file for complete search history.

(57) **CLAIM**

The ornamental design for a scanner, as shown and described.

DESCRIPTION

FIG. 1 is a perspective view of a scanner showing our new design;

FIG. 2 is a front view thereof;

FIG. 3 is a rear view thereof;

FIG. 4 is a left side view thereof;

FIG. 5 is a right side view thereof;

FIG. 6 is a plan view thereof;

FIG. 7 is a bottom view thereof; and,

FIG. 8 is a perspective view in which each tray is in the open position.

1 Claim, 6 Drawing Sheets
